UNITED STATES PATENT OFFICE.

EDGAR H. WISE, OF WESTMONT, PENNSYLVANIA.

RESISTANCE-PILE.

SPECIFICATION forming part of Letters Patent No. 727,249, dated May 5, 1903.

Application filed May 12, 1902. Serial No. 106,852. (No model.)

To all whom it may concern:-

Be it known that I, EDGAR H. WISE, a citizen of the United States, and a resident of the borough of Westmont, in the county of Cambria and State of Pennsylvania, have invented new and useful Improvements in Resistance-Piles, of which the following is a specification.

My invention relates to resistance-piles for electrical controllers and other purposes.

As generally constructed heretofore resistance-piles for electrical controllers and other purposes have employed a continuous wire possessing certain properties of resistance and wound spirally in a coil with or without a core or suitably arranged to provide for free radiation of heat incident to use and properly insulated. Such resistance-piles are more or less liable to derangement or "ground," bulky, and inconvenient to handle, expensive, and if fused in whole or in part from sudden subjection to excessive currents or from other causes are either entirely ruined or rendered difficult to repair.

One object of the present invention is the provision of an improved resistance-pile especially intended for use in connection with the type of electrical controller patented to me by United States Letters Patent No. 653,857, dated July 17, 1900, though adapted for use

in other connections, which will be compact, light, durable, cheap, and easy to manufacture, interchangeable, and convenient to handle, and in which liability of grounding and hazards of burning out or injury or destruction from any cause will be reduced to a minimum.

Another object is to dispense with the use of a continuous or integral resistance, such as wire, heretofore used in resistance-piles and provide an improved and novel resistance in which a maximum amount of resistance may be obtained in a minimum space, with all concomitant advantageous effects and the added advantages aforesaid.

A further object is the provision in a resistance-pile of a compound resistance medium which will render possible the rapid and convenient removal of any damaged portion thereof without interference with the integrity and utility of the pile.

Another object is to provide a novel resistance-pile in which provision is made for wir-

ing thereto, so that all or only a portion of the resistance of the pile may be utilized.

To accomplish the foregoing objects, I provide an improved and novel resistance-pile, the details of construction of which are set forth hereinafter, while the novelty embraced in the invention is recited in the appended claims.

In the accompanying drawings, Figure 1 is an elevation of the resistance-pile, parts being shown in section and the intermediate terminal plate being dispensed with. Fig. 2 is an elevation of the pile, showing the use of the intermediate terminal plate. Fig. 3 is a face view of a metal resistance-disk, showing the overlapping end of the asbestos or insulating disk on the opposite side thereof. Fig. 4 is a detail of an asbestos or insulating disk. Fig. 5 is a detail of a metal resistance-disk. Fig. 6 is a face view of one of the end terminal plates. Fig. 7 is a face view of the mica of the end terminal plates. Fig. 8 is a face view of the intermediate terminal plate of Fig. 2. Fig. 9 is a diagrammatical view illustrating the manner of wiring a set of piles when used in a controller. Fig. 10 is a detail view of a few of the metal resistance-disks and insulating-disks spread apart to illustrate how portions thereof overlap.

The core of the resistance-pile consists of an iron or steel rod 1, square in cross-section, as at 2, throughout its length, except at its ends 3, where it is screw-threaded. The squared portion 2 is incased in several layers of mica 4, though other insulating material could be employed if preferred.

The resistance proper is composed of metal laminae or disks 5. These will preferably be of sheet metal and of circular shape, and they are provided at their centers with square apertures 6 of a size to fit snugly, yet easily, on the mica covering 4, embracing the squared portion 2 of rod 1, which prevents them from turning or shifting. Each metal disk 5 is provided with a slit or cut 7, preferably made as a continuation of one side of aperture 6 and extending to the outer margin of the disk. The disks or laminae are so arranged or assembled on the core 1 that the slit or cut 7 of one disk is disposed a quadrant's distance or ninety degrees circumferentially from the next succeeding disk, and so on from one end

of the pile to the other. Interposed between adjacent disks is an insulating medium, preferably a disk 8, of asbestos, with similar square opening at the center to embrace the squared portion 2 of the core, and these asbestos disks are slit or cut at 9 in a manner similar in all respects to slitting of the metal disks 5, except that the slit of the asbestos disks 8 is made at right angles to the slit of the metal disk 5, and the substantially sector-shaped portions 10 and 11 of the metal disk 5 and asbestos disk 8, respectively, are overlapped, in consequence of which all portions of one metal disk or laminae 5 are insulated from a succeeding metal disk 5, except the sector portion 10, which bears directly against the succeeding metal disk 5 a quadrant's distance from the slit or cut of that succeeding disk. It will be understood from the foregoing description that the current passing through the pile will travel in a spiral direction from the point of entrance to the point of exit. Liquid glass is by preference used as a coating for the asbestos and metal disks, except where they overlap and make contact, or mica could be employed in place of the asbestos, if desired. The outermost metal disks 5—that is, those at the ends of the resistance-pile—make direct contact with their entire faces with the metal terminal plates 12, which have a central aperture or perforation 13 to receive the core or rod 1, and then are provided with elongated wire connectors or binding-posts 14, two being employed by preference and disposed substantially longitudinally at the ends of a diameter of the terminal plate. Disposed between these wire connectors and lying flat against the terminal plates are the insulating media 15, mica being preferred, through which the threaded ends 3 of the rod 1 project. On the ends of the rod and lying against the mica 15 are insulating-bushings 16, of fiber or molded mica, while 17 are clamping-nuts for clamping the pile together, and 18 are fastening-nuts for securing the pile in the controller or other place where used.

In order that less than the entire resistance of the pile may be used, according to requirements, I prefer to employ one or more intermediate terminal plates 19 on the rod 1 and located between the uninsulated faces of two of the disks 5. Such terminal plates will have wire connectors 20 and 21 on opposite sides and suitably notched at 22 to facilitate connection to the wires. The metal and insulating laminae are by preference coated exteriorly with insulating-paint.

The nuts 17 can be screwed as tightly as desired to clamp all the disks and parts together to secure rigidity and a perfect electrical contact between the metal disks and the fastening-nuts 18 utilized to secure the pile wherever needed. For instance, in using the pile on the type of controller embodied in my Patent No. 653,857, hereinbefore referred to, the end of the rod 1 will be inserted

in a hole in the bottom insulating-board and the nut 18 on that end backed up, which will push the upper end of the rod into the hole 70 in the upper insulating-board, and the nuts will lock the pile tightly in position.

In Fig. 9 I have illustrated diagrammatically the manner in which, say, six (the usual number employed in my controller) of the 75 piles can be wired to the connecting-board, thus permitting the utilization of one or more of the piles or a portion of any pile, from which the advantage of making provision for using only a portion of the resistance of a 80 pile will be apparent.

Having fully described my invention, what I claim as new, and desire to secure by Letters Patent, is—

1. A resistance-pile comprising alternately-arranged members of conducting and non-conducting material, said members slitted from the center to the outer edge and the end of one member extending through the slit of the other whereby said ends overlap in reverse position from that of their remaining portions. 85

2. A resistance-pile comprising alternately-arranged members of conducting and non-conducting material, said members slitted from the center to the outer edge and the end of one member extending through the slit of the other whereby said ends overlap in reverse position from that of their remaining portions, said reversely-overlapped pairs of 95 ends spirally arranged with relation to one another. 100

3. A resistance-pile composed of a plurality of alternately-arranged perfectly-flat disks of conducting and non-conducting material, 105 said disks so displaced and disposed at certain parts that a portion of one is in the plane of the other.

4. A resistance-pile composed of a plurality of alternately-arranged perfectly-flat disks 110 of conducting and non-conducting material, said disks so displaced and disposed at certain parts that a portion of one is in the plane of the other, said reversely-juxtaposed portions of the pairs of disks arranged spirally. 115

5. A resistance-pile composed of disks of conducting and non-conducting material alternately arranged, said disks each having a central opening, and a slit extending therefrom to the periphery, the disks crossing each 120 other through these slits.

6. A resistance-pile composed of alternately-arranged disks of conducting and non-conducting material, these disks perfectly flat and portions thereof crossed into each 125 other's planes, whereby portions of disks of the same material are in contact with each other.

7. A resistance-pile composed of alternately-arranged disks of conducting and insulating material, these disks perfectly flat and portions thereof crossed into each other's planes, whereby portions of disks of the same material are in contact with each other, and 130

- means for applying pressure inwardly upon the disks whereby they are held rigidly together and in intimate contact with one another.
- 5 8. A resistance-pile consisting of a resistance made up of sections or members and interposed insulating sections or members, said resistance members having overlapping portions and the overlapping portions of the resistance members being in direct electrical contact with adjacent resistance members and in spiral arrangement around a center.
- 10 9. A resistance-pile consisting of a resistance made up of disks or laminæ and interposed insulating-disks or laminæ, said resistance and insulating disks or laminæ being slit or cut inwardly from their peripheries, providing tongues or portions and said tongues or portions of the resistance-disks and insulating-disks overlapping and the overlapping tongues or portions on the resistance-disks being in electrical contact with adjacent resistance-disks in spiral arrangement.
- 15 10. A resistance-pile consisting of a resistance made up of disks or laminæ and interposed insulating disks or laminæ, said resistance and insulating disks or laminæ being slit or cut inwardly from their peripheries, providing tongues or portions and said tongues or portions of the resistance-disks and insulating-disks overlapping, and the overlapping tongues or portions on the resistance-disks being in electrical contact with adjacent resistance-disks, said tongues or portions on succeeding disks or laminæ of the series being
- 20
- 25
- 30
- 35

arranged at different points circumferentially in a progressive manner, whereby the current traversing the resistance-disks approximates a spiral path.

11. A resistance-pile, consisting of a core 40 or rod, and a resistance composed of disks or laminæ strung on said core and held against turning or shifting thereon, their contacts arranged spirally around a core.

12. A resistance-pile consisting of a core 45 or rod, and a resistance composed of disks or laminæ, provided with apertures corresponding to the conformation of the core or rods strung thereon, whereby they are prevented from turning or shifting on the rod or core, 50 the contacts of these disks arranged spirally.

13. A resistance-pile, consisting of a core or rod, a resistance composed of disks or laminæ strung in said rod and held against turning or shifting thereon, and insulating 55 disks or laminæ strung on the rod or core and interposed between the resistance disks or laminæ said resistance-disks and insulating-disks having overlapping portions whereby adjacent resistance-disks make electrical contact with each other in a spiral arrangement and continuity of said contact is preserved.

In testimony whereof I have signed this specification in the presence of two subscribing witnesses.

EDGAR H. WISE.
